CLAIM

The ornamental design for a pet ladder for training as shown and described.

DESCRIPTION

1. Pet ladder for training

Fig. 1.1 is a first perspective view of a pet ladder for training in accordance with the present design;

Fig. 1.2 is another perspective view thereof;

Fig. 1.3 is a front view thereof;

Fig. 1.4 is a back view thereof;

Fig. 1.5 is a left side view thereof;

Fig. 1.6 is a right side view thereof;

Fig. 1.7 is a top view thereof;

Fig. 1.8 is a bottom view thereof;

Fig. 1.9 is a closed state perspective view thereof;

Fig. 1.10 is another closed state perspective view thereof; and

Fig. 1.11 is an enlarged view of the area labeled '11' in the Fig. 1.1 view thereof.

Fig. 1.11 is an enlarged view of a portion indicated by the dash-dot-dash lines and number "11" in fig. 1.1; the dash-dot-dash lines and number "11" in fig. 1.1 are for the purpose of depicting the cut line of the enlarged view and form no part of the claimed design.
